UNITED STATES PATENT OFFICE.

DANIEL W. HOFERER, OF WHITTIER, CALIFORNIA, ASSIGNOR TO JOY J. RICHART, OF WHITTIER, CALIFORNIA.

PERFORATOR.

Application filed June 16, 1924. Serial No. 720,282.

This invention relates to a perforator, and has particular reference to a device for perforating pipe or casing in a well, or the like.

In the construction of a well, such as an oil well, it is the common practice to encase the walls of the well with a casing leading down to the formation from which the oil is to be produced. The lower end of this casing may be provided with a screen section through which the oil from the formation is to enter the well. In other cases, the lower end of the casing may be perforated after the casing is placed in the well in order to provide suitable screening openings for admission of the oil into the well. It frequently occurs that after the casing has been installed in a well, it is found that the first screen section or perforated section of the casing is improperly positioned so that the oil from the formation does not enter the well. In this case, it is necessary to perforate or form screening openings in the casing at a different position in order to permit ingress of the oil from the formation into the well bore. Moreover, frequently in the drilling of oil wells, a plurality of oil producing sands or formations will be encountered and it may be desirable to drill beyond the first oil producing formation into a lower producing formation to extract the oil first from the lower section. In this case, after the production from the lower formation has declined, it later becomes desirable to establish communication between the upper producing formation and the well bore. In such a case, it is necessary to provide suitable means by which the casing can be perforated at the desired points. Moreover, due to the various causes encountered in drilling or constructing a well, the producing formation may be shut off from the interior of the well bore by a plurality of strings of well casing. This happens when, for example, one well casing becomes stuck in the well bore or it is necessary to cement a string of casing in the well bore to shut off water and then later a second and smaller string is positioned within the well hole to permit extension of the well bore. Wherever the further drilling of the hole through such second casing establishes that it is desirable to back up and attempt production through points in the well above the bottom of the outer string, we have a condition where the

well bore is shut off from the formation by two separate casings.

Heretofore, the art has been provided with no satisfactory practical means by which communication could be had between a well bore and a formation where the well bore was separated from the formation by two casings and it was necessary to perforate through both casings.

It is an object of the present invention to provide a perforator for performing screening perforations in well casings or for forming other openings in well casings, which perforator is adapted to operate within a well bore and perforate through a plurality of casings which enclose the well bore from communication with the adjacent formation.

When it is desired to perforate through more than a single casing, it is necessary to provide a cutting tool having an exceptionally long blade which must in the operation of perforating a plurality of strings, project a very substantial distance from the exterior surface of the well perforating tool. Moreover, in order to permit the passage of such perforating tool through the well bore, in positioning the tool opposite the point to be perforated and in removing the tool after the perforating operation, it is necessary that this long cutting blade should be properly housed within the perforator body. Due to the length of such a cutting blade, it is therefore necessary that it lie in the body substantially longitudinally to the axis of the body. Therefore, when the cutting blade is moved to project from the body sufficiently to first engage the inner surface of the inner casing, it is at a very slight angle with the casing surface and the engagement between the casing surface and cutting blade is not sufficient to force the long cutting blade into a cutting position or to perforate through the casing. For this reason, the prior perforating tools have been confined to devices employing short cutting blades or points which were adapted only to perforate a single casing.

I have discovered that by the provision in a perforating tool of a cutter provided with a plurality of cutting blades rigidly attached together and forming part of one pivotally mounted cutting member, and by forming one of these blades of short length and arranged to lie at a different angle rela-

tive to the axis of the body than the other blade, which is constructed of sufficient length to perforate two casings, the shorter blade may be brought into position with the 5 inner casing in such position as to cut into the casing sufficiently to form a positive leverage point which will force the other longer blade into the casing to perforate the same despite the slight angle of original approach of such longer cutter.

Other features of the invention include the provision of means for initially advancing at will the cutter of the perforator to position first only the shorter blade of the cutter in position to engage with the casing of the well, which means are operative from the top of the well, as desired.

The various objects and features of this invention will be best and more fully understood from the following detailed description of a typical preferred form of the invention throughout which description reference is had to the accompanying drawings in which

23 Fig. 1 is a side elevation of the perforator provided by this invention showing it completely collapsed or unactuated.

Fig. 2 is a vertical detailed sectional view of the perforator showing it unactuated.

29 Fig. 3 is a view similar to Fig. 2 showing the perforator partially actuated.

Fig. 4 is a side elevation of the perforator, being a view taken as indicated by line 4-4 on Fig. 2.

33 Fig. 5 is a vertical detailed sectional view of the perforator being a view taken as indicated by line 5-5 on Fig. 2.

Fig. 6 is a detailed transverse sectional view of the perforator taken as indicated 40 by line 6-6 on Fig. 2.

Fig. 7 is a detailed transverse sectional view of the perforator taken as indicated by line 7-7 on Fig. 2.

45 Fig. 8 is a detailed transverse sectional view of the perforator taken as indicated by line 8-8 on Fig. 2.

Fig. 9 is a detailed transverse sectional view of the perforator taken as indicated by line 9-9 on Fig. 2.

50 Fig. 10 is a detailed transverse sectional view of the perforator taken as indicated by line 10-10 on Fig. 2, and

Fig. 11 is a detailed sectional view taken as indicated by line 11-11 on Fig. 7.

55 The device provided by this invention is intended primarily for use in perforating casings, or the like, in a well. The invention is of particular value in perforating a doubly-encased well hole. By a doubly-encased

60 well hole is meant a well hole in which there are two metallic casings telescoped one over the other or a well hole in which there is one metallic casing and a surrounding encasement of cement.

65 The present invention provides, generally,

a body 10, a cutter 11 carried by the body, and means 12 for actuating the cutter. The body 10 is an elongate member preferably formed of a single piece of material. The body is shaped, particularly with reference 70 to its cross sectional configuration so that it will properly operate in the innermost casing to be perforated and may be provided at its upper end with a tapered screw threaded projection or pin 13 by which it may be 75 connected with a suitable operating means, for instance, a string of drill pipe.

The body 10 forms a frame or carrier for the other parts of the device, and is provided with an opening 14 for the reception for the 80 other parts. In accordance with the preferred form of the invention the opening 14 is in the form of a groove in one side of the body and extends longitudinally of the body as clearly shown in Fig. 4 of the drawings. The groove 14 starts at the lower end of the body and extends upwardly in the body a considerable distance. The groove is comparatively narrow and deep and has sockets 15 at opposite points in its side and 85 walls 16 near its upper end. The sockets 15 are round and are formed in the sides 16 adjacent the bottom 17 of the groove. Recesses 18 are formed at opposite points in the sides 16 immediately beyond for instance above 90 the sockets 15. The recesses extend inwardly from the top or outer part of the groove and communicate with or join the sockets 15 in the manner clearly illustrated in Fig. 11 of the drawings. The inner or bottom portion of the groove is enlarged for a considerable distance upwardly from the lower end of the body. The enlarged part 19 may be formed by cutting away the sides of the groove, for instance, by boring from the 100 lower end of the body, and is terminated at its upper end by downwardly facing shoulders 20.

The cutter 11 is carried by the opening in the body so that it is movable from a position where it is completely in the body and has no part projecting or protruding from the body to a position where it has parts projecting a substantial distance from one side to the body. The main portion or shank 21 of the cutter slidably fits between the sides 16 of the groove 14 and is provided at its inner end with trunnions 22, which support the cutter for movements in a plane longitudinally of the casing being perforated. 110 The trunnions 22 extend from opposite sides of the cutter and are adapted to fit or be carried in the sockets 15 in the walls of the groove 14. The trunnions are preferably solid or integral with the shank of the cutter and are adapted to be arranged in and removed from the sockets 15 through recesses 18. The trunnions 22 are retained in the sockets 15 by retaining blocks 24 arranged in the recesses 18 to extend inwardly 115 120 125

- over the trunnions in the manner clearly illustrated in Fig. 11 of the drawings. The retaining blocks 24 are preferably made to completely fill the recesses 18 and are secured 5 in place by suitable means, say for instance, by means of screws 25 which extend into them from the exterior of the body 10, as clearly illustrated in Figs. 5, and 6 of the drawings.
- 10 When the cutter 11 is in its normal or un-actuated position its main portion or shank 21 hangs downwardly in the groove 14 in the body and no part of the cutter projects or protrudes from the body. In the case of 15 a tool for operating on the plurality, say two, casings at a time, the cutter is provided at its outer part with two cutting parts 30 and 31. The cutting parts are formed directly on the outer part of the shank of the 20 cutter and are of different lengths; the short cutting part 30 being adapted to engage and cut through the innermost casing indicated at A in Fig. 3 and the long cutting part 31 being adapted to extend through the inner 25 casing A and through the outer casing B. The two cutting parts 30 and 31 extend in different directions with reference to the pivotal axis of the cutter. The short cutting part 30 is at the upward or leading portions 30 of the shank so that it is the first to project from the body 10 when the device is operated. In practice, the cutter is designed and proportioned so that the short cutting part 30 engages or operates on the inner casing A 35 before the long cutting part engages the inner casing. In Fig. 3 of the drawings, I have illustrated the cutter partially actuated in which position the short cutting part is operating upon the inner casing A while 40 the long cutting part is just coming into engagement with the casing A. It will be obvious, of course, that the cutting parts may in practice be varied in size, shape and arrangement depending upon the character 45 of perforators desired, the casings to be perforated, etc.
- The cutter actuating means 12 provided by the present invention to actuate the cutter 11, includes, generally, a wedge 40 slidably carried in the groove 14 in the body 10, a tail piece or other suitable devices 41 located below the lower end of the body 10, and a tail rod 42 connecting the tail piece and wedge. The wedge 40 may be in the 50 form of a block slidably fitting the groove 14. The wedge is provided at opposite sides with projections 43 which extend into the enlarged portion 19. The projections have flat upper ends 44 forming shoulders adapted to engage and cooperate with the shoulders 20 at the upper ends of the enlargement 19. The upper part or end of the wedge 40 has an upwardly and inwardly inclined wedge face 46 adapted to cooperate 55 with the cutter to move or force it out when the wedge is moved upwardly. The parts are arranged and proportioned so that the wedge upon being moved upwardly engages behind the long cutting part 31 and forces or swings the cutter outwardly in the direction indicated by the arrow C in Fig. 3 to or beyond a position where the short cutting part 30 has engaged or entered the inner casing A. The projections 43 in the wedge are made to more or less accurately fit the enlargement 19 in the groove so that they operate to guide the wedge in its movement. Further the enlargement 19 and the projections 14 are proportioned and related so that the shoulders 20 and 44 cooperate to 60 limit the upward movement of the wedge so that the wedge cannot be forced too far upwardly and cannot injure the cutter.
- 65 The tail piece 41 may, as far as the present invention is concerned, be any suitable device or arrangement operable to engage in a casing for the purpose of establishing a fixed or substantially fixed part with relation to which the body of the device may be moved. In practice I have employed an ordinary type of tail piece which can be tripped at the desired point to expand and grip the casing A in a manner so that it offers considerable resistance to movement in the casing. The tail rod 42 is preferably a 70 plain rod having its upper end fixed to the wedge 40 and its lower end connected to the tail piece 41.
- A block 50 is preferably arranged in the lower end of the groove 14 to guide the tail 75 42 and to form a stop for the downward movement of the wedge so that the wedge will not become displaced from the body. The block 50 may be secured in place by means of screws 51 so that it can be readily 80 removed if necessary.
- 85 It is desirable to limit the upward swinging movement of the cutter 11, for instance, by means of a suitable shoulder 60 in the groove 14 to cooperate with or be engaged by the shank of the cutter. In the preferred arrangement the stop shoulder 60 is formed on a block 61 adapted to be arranged in the upper end in the groove 14 in the manner clearly shown in Figures 2, 3 and 5 of the 90 drawings. The block 61 may be retained in place by means of a suitable pin 62.
- 95 In operation the device is lowered into the inner casing A on the end of a suitable operating member, for instance, a string of 100 drill pipe. At the desired point in the casing A the tail piece is tripped or actuated, the particular operation manipulated necessary for this depending upon the nature of the tail piece. With the tail piece 41 set 105 to gripping the casing A so that it will not readily move therein, and with the other parts of the device unactuated as illustrated in Figs. 1 and 2 of the drawings, the body 110 10 is moved or forced downwardly so that 115

the wedge 40 which is stationary with the tail piece engages the cutter to operate it until the short cutting part 30 engages or enters casing A. As the body 10 is moved 5 further downwardly the engagement of the short cutting part 30 with the casing A causes the cutter to continue to operate in the direction indicated by the arrow C in Fig. 3 so that the long cutting part 31 10 passes outwardly through the casing A and through the casing B. When this operation is completed the device is returned to its normal position by upward movement of the body 10.

15 Having described only a typical preferred form of my invention I do not wish to limit myself to the specific details hereinabove set forth but wish to reserve to myself any changes or variations that may appear to 20 those skilled in the art or fall within the scope of the following claims.

Having described my present invention, I claim—

1. A casing perforator including, a body, 25 a cutter pivotally carried by the body, the cutter having cutting parts of different lengths and being movable in a plane longitudinally of the casing being perforated between a position where it is within the body 30 and a position where its cutting parts project from the body, and means for actuating the cutter.

2. A casing perforator including, a body, and a cutter carried by the body, the cutter 35 having two cutting parts of different lengths and being movable in a plane longitudinally of the casing being perforated between a position where it is within the body and a position where its cutting parts project from 40 the body, the cutting parts being related so that the short cutting part is the first to project from the body when the cutter is actuated.

3. A casing perforator including, a body, 45 and a cutter carried by the body, the cutter having two cutting parts of different lengths and being operable in a plane longitudinally of the casing being perforated and from a position where the cutting parts are within 50 the body to a position where they project from the body, the cutting parts being related so that the short one is first to project from the body when the cutter is actuated, and means for positively actuating the 55 cutter until the short cutting part projects from the body.

4. A casing perforator including a body having a groove, there being sockets at opposite points in the sides of the groove, there being recesses at opposite points in the sides of the groove communicating with the socket, a cutter, trunnions extending from opposite sides of the cutter and adapted to be arranged in the sockets through the 60 recesses, the cutter being operable in a plane

longitudinally of the casing being perforated, and means for closing the recesses.

5. A casing perforator including a body having a longitudinal groove extending upwardly from its lower end, there being 70 sockets at opposite points in the sides of the groove near the upper end of the groove, there being recesses at opposite points in the sides of the groove communicating with the sockets, a cutter having two cutting 75 parts of different lengths, trunnions extending from opposite sides of the cutter adapted to be arranged in the socket through the recesses, blocks adapted to be arranged in the recesses to retain the trunnions in the 80 sockets, an enlarged portion in the lower end of the groove terminating in a downwardly facing shoulder, a wedge slidably carried in the groove below the cutter to cooperate with the cutter to move it to a position 85 where the cutting parts project from the body, a projection on the wedge operating in said enlarged portion and presenting a shoulder to cooperate with said first mentioned shoulder to limit the upward movement of the wedge, a tail rod connected with the wedge and extending downwardly therefrom to a point below the lower end of the body, and a block arranged at the lower 90 end of the body to guide the tail rod and limit the downward movement of the wedge.

6. A casing perforator including a body, a cutter pivotally mounted in said body and including two cutting parts extending radially from the pivotal axis of the cutter, the cutting parts being of different lengths and related so that the shortest one operates before the longest one, said cutter being mounted for cutting movement in a plane 100 longitudinally of the casing being perforated.

7. A casing perforator including a body, a cutter including two cutting parts carried by the body operable to project different 110 distances from the body, the cutting parts being related so that the cutting part projecting the shorter distance from the body operates first and aids the operation of the other cutting part, said cutter being mounted for cutting movement in a plane longitudinally of the casing being perforated.

8. A casing perforator adapted for forming screening openings in the casings of a doubly encased well hole, comprising a body, a cutter pivotally carried by the body, for movement in a plane longitudinally of the casing being perforated, said cutter having blades of different lengths, one adapted to engage the inner casing and operative as a feeding element for rotating the cutter to force the other blade into perforating position, the other blade being of a length sufficient to perforate both casings, the cutting blades being set at an angle one to the other.

9. A casing perforator adapted for form-

- ing apertures in the casings of a doubly encased well hole, comprising a body adapted to be lowered into a well hole, a cutter carried by the body and movable in a plane longitudinally of the casing being perforated from a closed position within the body to a perforating position from the force imparted to the cutter by the relative longitudinal motion between the casing and body,
- 10 the cutter having blades of different lengths, one adapted to engage the inner casing and operate as a feed element for rotating the cutter to force the other cutting blade into the perforating position on longitudinal motion of the perforator, the other blade being of a length sufficient to perforate both casings.
10. A casing perforator adapted for forming screening openings in the casings of a doubly encased well hole, comprising a body lowerable into the well bore, a cutter carried by the body, the cutter having blades of different lengths, one blade being adapted to engage the inner casing and operate as a feeding element for rotating the cutter to force the other blade into the perforating position, such action taking place through a longitudinal motion of the perforator, the other blade being of a length sufficient to
- 30 perforate through both casings in the perfo-

rating position, the cutter being housed in the body in one position so that it is protected from engagement with the well casing, and an anchor member carried by the body and operative to engage the casing to 35 initially translate the cutter into position where the first or shorter cutting blade is in engagement with the well casing.

11. In a casing perforator adapted for forming apertures in casings of a doubly encased well hole, the combination of a body, a cutter carried by the body and provided with cutting blades, one cutting blade being adapted to engage the inner casing to operate as a feeding element for rotating the 45 cutter to force the other blade into the perforating position upon a longitudinal movement of the body, said other blade being of a length sufficient to extend laterally from the body and perforate both casings in the 50 perforating position, and a tail anchor slidably secured to the body and provided with a wedge operating to translate the cutter to position in which the shorter cutting blade is in engagement with the well casing. 55

In witness that I claim the foregoing I have hereunto subscribed my name this 10th day of June 1924.

DANIEL W. HOFERER.
